UNITED STATES PATENT OFFICE.

JULIUS S. NEWLAND, OF CARSON CITY, NEVADA.

DESIGN FOR A SAND-BAND CAP.

SPECIFICATION forming part of Design No. 15,625, dated December 16, 1884.

Application filed October 16, 1884. Term of patent 14 years.

To all whom it may concern:

Be it known that I, JULIUS S. NEWLAND, of Carson City, in the county of Ormsby and State of Nevada, have invented and produced a new and original Design for a Sand-Band Cap for the Hubs and Axles of Vehicle-Wheels, of which the following is a full, clear, and exact description.

My design for a sand-band cap for the inner ends of the hubs of wagons and other vehicle-wheels and axles thereof consists in an axle-protecting cap of broken circular form, representing a disk interrupted below by an opening extending up through its face to near its top, said opening presenting parallel sides for the greater portion of its height, but of arched form at its upper end, and ornamented by a projecting arch at its upper portion on the face of the broken disk, the outer margin of which shows an inner turned rim or flange throughout its length.

Reference is to be had to the accompanying drawing, forming part of this specification, which represents a view in perspective of a sand-band cap embodying my design.

The outer face, *b*, of the cap is of broken-disk form, being interrupted below by an

opening, *c*, which extends upward to near the top of the disk, and which presents parallel sides for the greater portion of its height, terminating in an arched form above. The upper portion of said opening is ornamented by a projecting arch, *d*, on the outer face of the disk, corresponding to the shape of the opening in the disk, and the outer margin of the broken disk is made to present an inner turned rim or flange, *e*, extending throughout its length.

I claim—

The within-described design for a sand-band cap, the face *b* of which is of partial-disk form, with an inner border or rim, *e*, extending throughout the length of the broken disk, and having the opening *c* up within it, presenting parallel sides for the greater portion of its height, terminating in an arched form above, and bound or ornamented on the outer face of the disk by a projecting arch, *d*, corresponding in shape to the opening in the disk, as shown.

JULIUS S. NEWLAND.
